Primary Examiner—Robert M. Spear(74) *Attorney, Agent, or Firm*—Richardson & Folise**(57) CLAIM**

The ornamental design for a twist lid, as shown and described.

DESCRIPTION

FIG. 1 is a right side perspective view of a twist lid showing our new design; the lid is shown attached to a beverage container shown in phantom which is for illustrative purposes only and forms no part of the claimed design.

FIG. 2 is a top plan view thereof.

FIG. 3 is a front elevational view thereof.

FIG. 4 is a left side elevational view thereof the right side elevational view thereof being a mirror image thereof; and, FIG. 5 is a rear elevational view thereof.

The surfaces or portions of the article not shown in the drawings or described in the specification form no part of the claimed design.
